UNITED STATES PATENT OFFICE

114,101

DESIGN FOR A WALL LAMP OR SIMILAR ARTICLE

Roscoe C. Gregg, Fredericktown, Ohio

Application February 7, 1939, Serial No. 82,852

Term of patent 3½ years

To all whom it may concern:

Be it known that I, Roscoe C. Gregg, a citizen of the United States, residing at Fredericktown, in the county of Knox and State of Ohio, have invented a new, original, and ornamental Design for a Wall Lamp or Similar Article, of which the following is a specification, reference being had to the accompanying drawing, forming a part thereof.

Fig. 1 is a perspective view of a wall lamp or similar article showing my new design;

Fig. 2 is a front elevational view;

Fig. 3 is a top plan view thereof.

I claim:

The ornamental design for a wall lamp or similar article, as shown.

ROSCOE C. GREGG.
